Primary Examiner — Wan Laymon*Assistant Examiner* — Clint A Samuel(74) *Attorney, Agent, or Firm* — Miller & Martin PLLC; Stephen J. Stark(57) **CLAIM**

The ornamental design for a bottle opener, as shown and described.

DESCRIPTION

FIG. 1 is a perspective view of a bottle opener showing our new design;

FIG. 2 is a top elevational view thereof;

FIG. 3 is a bottom elevational view thereof;

FIG. 4 is a right side elevational view thereof; the left side elevational view thereof being a mirror image thereof;

FIG. 5 is a rear elevational view thereof; and,

FIG. 6 is a front elevational view thereof.
